HARRY STEINFIELD, OF NEW YORK, N. Y., ASSIGNOR OF THREE-TENTHS TO EDWARD ERVIN AND ONE-FIFTH TO CLAIRE TAMAGNO, BOTH OF NEW YORK, N. Y.

COMPACT LIGHTER

Application filed May 29, 1930. Serial No. 457,412.

My invention relates to improvements in compact lighters for cigarettes, cigars, or the like.

In accordance with my invention, I provide a compact lighter which is relatively long and slender, and may be conveniently carried by a lady in her purse or bag. The lighter has a fuel reservoir of large capacity, thereby eliminating frequent refilling of the same. 10 The device also embodies a burner element, which may be removed for the insertion of the wick, rendering it convenient to pass the wick through the burner element and also rendering it possible to obtain a tight fit between the wick and burner element for properly closing the reservoir, and thereby preventing unnecessary evaporation of the fuel. The lighter further preferably embodies a plurality of flints, in conjunction with a movable striking element, thereby assuring spark or sparks upon each stroke of the striking element. The burner is enclosed within a guard or windshield having an opening in one side of the same for the insertion of the 20 end of the cigarette or the like, whereby the flame will not be readily blown out when the lighter is used in the open. The guard or windshield is adapted to be covered by a cap, preferably having telescoping engagement therewith, and this cap is attached to the striking element to be moved thereby. The device further embodies a snuffer movable with the cap and when in the closed position has a close fit with the burner element, positively preventing the escape of fumes from the fuel which is drawn to the burning end of the wick by capillary attraction, thereby preventing these fumes coming in contact with the flints, whereby the flints are maintained dry and hard and will at all times properly produce sparks. The construction is such that the fuel, either liquid or solid, may be fed into the reservoir without liability of the same overflowing and coming in contact with the flint or flints, which are completely sealed from the fuel during the refilling process. Means are also provided so that the guard or windshield cap may be separated from the striking element to afford ready access to the burner element. Means

are also provided whereby the striking element, at will, may be locked in the forward position, thereby holding the guard or windshield cap in the open position, so that the lighter may be used by a number of persons 55 without repeated operation.

The foregoing are some of the features and advantages of the device, but it is obvious that the invention resides in various combinations of elements not including all of these 60 features, as defined by the claims.

In the accompanying drawings, forming a part of this specification, and in which like numerals are employed to designate like parts throughout the same,

Figure 1 is a side elevation of a compact lighter embodying my invention, the cap being closed,

Figure 2 is a similar view with the cap open,

Figure 3 is a longitudinal section taken on line 3—3 of Figure 2,

Figure 4 is a transverse section taken on line 4—4 of Figure 3,

Figure 5 is a similar view taken on line 75 5—5 of Figure 1,

Figure 6 is a similar view taken on line 6—6 of Figure 3,

Figure 7 is a central vertical longitudinal section through the body portion of the device.

In the drawings, wherein for the purpose of illustration, is shown a preferred embodiment of my invention, the numeral 10 designates a body portion, which may preferably be a metal casting. A tubular flame guard or windshield 11 is preferably formed integral with this body portion and projects forwardly therefrom and has its forward end open and is provided in its periphery or 80 side with an opening 12, as shown.

The body portion 10 is provided with an opening 13, for the passage of a wick, to be described, and for the introduction of the fuel, liquid or solid, into the fuel reservoir or 95 tank. The opening 13 leads at its forward end into a screw-threaded opening 14, preferably arranged at an angle with relation thereto, and this screw-threaded opening receives a screw-threaded shank 15 of a re- 100

movable burner element 16, holding the wick 17, as shown. There is a particular advantage in having the burner element removable, inasmuch as it renders it more convenient to insert the wick into the burner element, and further it is possible to use a wick having as tight a fit as possible with the burner element to prevent unnecessary evaporation of the fuel. The opening 13 also has communication with a radial or laterally projecting screw-threaded opening 18, which is adapted to be covered by a screw-threaded plug 19.

The body portion 10 also has an opening 20 formed therein, for slidably receiving a reciprocatory combined operating and striking element 21.

The body portion 10 is provided at its rear end with an annular flange 22, receiving thereon a tubular casing 23, which is preferably permanently attached thereto by soldering or the like. The tubular casing 23 is preferably cylindrical and has a considerably greater length than diameter. The element 21 extends longitudinally through the casing 23, adjacent to one side of the same, while a fuel reservoir or tank 24 extends longitudinally within the casing, upon one side of the element 21. This reservoir 24 is preferably circularly curved in cross section with a flat side 25, arranged adjacent to the element 21, for providing a suitable space for the same. The forward open end of the reservoir 24 projects into the flange 22 and is preferably permanently attached thereto by soldering or the like.

The numeral 26 designates a reciprocatory tubular plunger mounted within the rear end of the casing 23, to telescope therewith. This tubular plunger receives the rear end of the element 21 and a transverse extension or bent end 27 thereof. The extension 27 has a screw-threaded opening for receiving a screw-threaded pin 28 also engaging within the screw-threaded opening 29 of a coupling disc 30, which is mounted in the rear end of tubular plunger 26, and preferably rigidly held therein by soldering or the like. The tubular plunger 26 preferably has a radially projecting lug 31, which may be stamped therefrom, and this lug operates within an L-shaped groove or guide 32, having a longitudinal extension 32' at the end of its transverse portion, the same being formed upon the inner side of the casing 23. It is thus seen that when the plunger 26 is moved to the forward position, it may be locked in such position by turning the plunger 26 slightly to the left, for bringing the lug 31 into the transverse end portion of the L-shaped groove. This turning movement is permitted by the fact that the coupling disc 30 will be slightly unscrewed upon the screw-threaded pin 29. When the plunger is not thus turned, it is free to reciprocate. The

extension 27 engages a suitably stiff compressible coil spring 33, the forward end of which engages the rear end of the reservoir 24, this spring being completely enclosed by the telescoping tubular plunger 26 and casing 23.

The body portion 10 is provided upon its side opposite the element 21 with generally radially disposed bosses 34, preferably cast integral therewith, and these bosses are angularly arranged and converge toward the element 21. These bosses constitute flint holders and have openings 35 slidably receiving the flints 36. These flints are accordingly held in an angular position and converge forwardly so that their forward ends are arranged in close relation and adapted to be engaged by the serrated or roughened surface 36a of the combined operating and striking element 21. The forward striking ends of the flints are arranged within a recess 37, formed by a beveled face 38 of the body portion 10, whereby a wholly unobstructed space is afforded between the flints and the wick. The bosses 34 have screw-threaded openings 35', which are larger in diameter than the openings 35, for receiving adjustable pressure regulating screws 36', acting upon springs 37', arranged between the screws and flints. These screws have cylindrical milled heads 38', operating within openings 39', formed in the outer ends of the bosses, and these openings extend through flat faces 40' of the bosses. The cylindrical heads 38' project radially beyond the opposite flat faces 40' and may be engaged by the thumb and finger, for conveniently adjusting the screws to regulate the pressure upon the flints.

The guard 11 slidably receives thereon a reciprocatory cap 39, having its rear end preferably beveled to fit closely upon a beveled shoulder 40, formed upon the body portion. When in the closed position, this cap covers the opening 12 in the guard 11. A coupling disc 41 is rigidly secured within the forward end of the cap 39, by soldering or the like, and preferably has a screw-threaded opening 42, for receiving the reduced screw-threaded end 43 carried by the element 21. The cap 39 reciprocates with the element 21. By shifting the plunger 26 to the forward position, it may be turned to bring lug 31 into the rear end of groove extension 32', subsequently to which the plunger 26 may be moved to the forwardmost position. This will move the cap 39 to the forwardmost position, so that its rear end will clear the forward end of the guard 11, whereby the cap may be rotated and unscrewed from the element 21, thus affording free access to the burner element, through the forward open end of the guard 11.

The coupling disc 41 has a leaf-spring 42 attached thereto by means of a rivet 43, or

the like, and this spring has an opening 44, formed therein, for receiving a headed shank 45, carried by a snuffer 46. The opening 44 is larger in diameter than the shank 45, af-
 5 fording a loose or universal connection be-
 tween the snuffer and the spring. The snuff-
 er has an inner beveled or tapered face 46,
 at its open end, to engage with a beveled
 outer or tapered face 47, formed upon the
 10 burner element 16. These tapered faces are
 provided so that the snuffer will be self-seat-
 ing upon the burner element, for affording a
 gas-tight joint. When the snuffer element
 15 is in the seated position, it encloses the free
 end of the wick, positively preventing the
 escape of the volatilized fuel, thereby retaining
 these vapors out of contact with the flints,
 and further eliminating odors, and unneces-
 20 sary loss of fuel, as much as possible.

The operation of the lighter is as follows:
 The casing 23 may be conveniently held be-
 tween the index finger and the second finger
 with the plunger 26 extending toward the
 25 thumb to be engaged thereby. The plunger
 is now pressed forwardly by the thumb with
 relation to the casing, causing the element 21
 to move forwardly. This forward movement
 30 of the element 21 shifts the cap 39 to
 the open position, the snuffer moving with
 the cap to the open position, and about the
 same time the striking surface 36^a is brought
 35 into engagement with the flints, producing
 spark or sparks which ignite the wick. As
 soon as the plunger 26 is released, the spring
 40 33 automatically returns the elements to the
 normal closed position. If it is desired to
 have the lighter used by a number of per-
 sons, the plunger 26 is forced forwardly, as
 45 described, and then turned slightly to the left
 for locking the same in the forward position.
 The cap 39 and associated elements
 will then be held in the open position until
 50 the plunger is released by a reverse turning
 movement, at which time the cap and asso-
 ciated elements are again automatically re-
 turned to the closed or starting position by
 55 the spring 33. It is thus seen that I have
 provided a lighter which is extremely simple
 in operation, inasmuch as all parts are shift-
 ed by the simple pressing of the plunger, and
 these parts automatically return to the start-
 60 ing position when the plunger is released.
 The lighter is preferably cylindrical and is
 slender, and is of the general shape of a lip-
 65 stick, fountain pen, or the like, and may be
 manufactured suitably small so that it can
 be conveniently carried in the purse or bag
 of a lady, or it may be equipped with a clip,
 as is customary with fountain pens, so that
 70 it may be attached to the apparel of a gentle-
 man.

It is to be understood that the form of my
 invention, herewith shown and described, is
 75 to be taken as a preferred example of the
 same, and that various changes in the shape,

size and arrangement of parts may be resort-
 ed to, without departing from the spirit of
 my invention, or the scope of the subjoined
 claims.

Having thus described my invention I claim:

1. A compact lighter comprising a long slender casing having means for holding a fuel, a burner element connected with the casing near one end for holding a wick, a cap 75 slideable longitudinally upon the end of the casing adjacent to the burner element to cover and uncover the same, flint holding means arranged near the burner element, a reciprocatory rod extending longitudinally through 80 the casing and having detachable connection with the cap, said reciprocatory rod having striking means bodily mounted thereon to reciprocate therewith, and a spring pressed plunger engaging the opposite end of the cas- 85 ing and connected with the rod.

2. A compact lighter comprising a long slender casing having means for holding a fuel, a burner element connected with the casing near one end of the same for holding 90 a wick, a cap slideable longitudinally upon the casing adjacent to the burner element to cover and uncover the same, a reciprocatory rod extending longitudinally through the casing and having striking means which is 95 bodily mounted upon the reciprocatory rod to reciprocate therewith, flint holding means arranged near the burner element for coaction with the striking means, a spring-pressed reciprocatory plunger engaging the opposite 100 end of the casing and connected with the reciprocatory rod, and means for locking the plunger in the inner position.

3. A compact lighter comprising a casing having fuel holding means, a pair of tubular 105 flint holding elements connected with the cas-
 ing and having bores for receiving the flints,
 said bores being inclined and converging in-
 wardly toward the casing, the arrangement
 bringing the inner ends of the flints into
 close relation and affording a space between
 110 them, a movable striking element carried by
 the casing and movable across the inner adjac-
 ent ends of the flints to simultaneously act
 upon the same, and a burner element for
 receiving a wick passing into the fuel holding
 115 means, said burner element being arranged
 between the bores of the tubular flint holding
 elements and having its free end adapted for
 communication with the space between the 120 flints.

4. A compact lighter comprising an elongated relatively slender casing, a liquid fuel reservoir extending longitudinally within the casing, a body portion secured to one end 125 of the casing and having a pair of inclined
 tubular flint holding elements which project
 radially beyond the casing and converge in-
 wardly toward the same, the arrangement be-
 ing such that the flints are held in a converg- 130

ing relation with their inner ends in close relation and a space between the flints, a burner element connected with the body portion for receiving a wick passing into the liquid fuel reservoir, the free end of the burner element being arranged for communication with the space between the flints, a reciprocatory rod operating within the casing and having a striking surface to engage with the inner ends of both flints, and means to move the rod.

5. A compact lighter comprising an elongated relatively slender casing, liquid fuel holding means extending longitudinally within the casing and spaced from one side thereof to provide a passage, a body portion secured to one end of the casing and having a pair of inclined inwardly converging bores, the inner ends of the bores terminating in close relation, said body portion also having a longitudinal bore arranged between the inclined bores, a burner element secured at the longitudinal bore and held between the inclined converging bores which receive the flints, a reciprocatory rod arranged within the casing and extending longitudinally through the passage and having a striking surface to engage the adjacent inner ends of the flints, a reciprocatory cap carried by one end of the rod and adapted to cover and uncover the burner element, and a reciprocatory plunger connected with the opposite end of the rod and disposed adjacent the opposite end of the casing.

35. 6. A compact lighter comprising an elongated relatively slender casing, a body portion secured to one end of the casing and having a transverse flint holding bore and also having a longitudinal passage, a tubular guard secured to the body portion and having an opening in its side, a reciprocatory cap mounted upon the tubular guard to cover and uncover the opening, a liquid fuel reservoir arranged within the casing and having a portion spaced therefrom for providing a passage, a burner element carried by the body portion to receive a wick leading to the liquid fuel reservoir, a reciprocatory rod extending through the longitudinal passage of the body portion and through the passage between the reservoir and casing and having one end attached to the cap and also provided with a striking surface to engage the flint, a plunger arranged at the opposite end of the casing and connected with the reciprocatory rod, and yielding means to oppose the inward movement of the plunger.

7. A compact lighter comprising an elongated relatively slender casing, a body portion secured to one end of the casing and having a transverse flint holding bore and also having a longitudinal passage and a longitudinal bore, a tubular guard secured to the body portion and having an opening in its side, a reciprocatory cap mounted upon the

tubular guard to cover and uncover the opening, a liquid fuel reservoir arranged within the casing and extending longitudinally thereof and having a portion thereof spaced from the casing for affording a longitudinal passage, a burner element carried by the body portion adjacent to the longitudinal bore to receive a wick which extends through the longitudinal bore into the fuel reservoir, a reciprocatory rod extending through the longitudinal passage of the body portion and through the passage between the reservoir and casing and having one end attached to the cap and also provided with a striking surface to engage the flint, a leaf spring arranged within the cap and attached thereto, a snuffer cap having a universal pivotal connection with the spring and adapted to automatically seat upon the burner element, a plunger arranged at the opposite end of the casing and connected with the reciprocatory rod, and a spring to oppose the inward movement of the plunger.

8. A lighter comprising a long slender casing having fuel holding means, a pair of flint holding elements connected with the casing and disposed transversely of the casing, the arrangement being such that a space is provided between the flints, a burner element for receiving a wick passing into the fuel holding means, said burner element having its free end in communication with the space between the flints, a reciprocatory rod connected with the long slender casing and extending longitudinally thereof and having a part projecting beyond one end of the casing, said reciprocatory rod having striking means bodily mounted upon the rod to reciprocate therewith and arranged to engage with the flints.

9. A lighter comprising a casing having fuel holding means, a pair of flint holding elements connected with the casing and arranged transversely thereof, the arrangement being such that a space is afforded between the flints, a burner element receiving a wick passing into the fuel holding means and so arranged that its free end is adapted for communication with the space between the flints, and a reciprocatory striking element for engaging both flints, said reciprocatory element extending longitudinally of the casing and moving generally at a right angle to the direction of the flints.

In testimony whereof I affix my signature.
HARRY STEINFIELD.
